UNITED STATES PATENT OFFICE.

SIEGMUND LANDSBERG, OF NEW YORK, N. Y.

DESIGN FOR EMBROIDERY.

SPECIFICATION forming part of Design No. 13,273, dated August 29, 1882.

Application filed July 20, 1882. Term of patent 7 years.

To all whom it may concern:

Be it known that I, SIEGMUND LANDSBERG, a citizen of the United States, residing at New York, in the county and State of New York, have invented and produced a new and original Design for Embroidery, of which the following is a specification, reference being had to the accompanying drawing, forming part thereof.

10 This design relates to a leaf formed of a raised border of chain-stitches and a filling of threads extending from one border to the other.

The accompanying drawing represents a face view of my design.

15 In this drawing, the letter A designates an embroidered leaf, which is provided with a raised border, *a*, formed of chain-stitches, the

space inclosed by said border being filled up by threads *b*. By the chain-stitch border *a* a novel and ornamental appearance is imparted 20 to the leaf A.

What I claim as new, and desire to secure by Letters Patent, is—

The design for an embroidered leaf, consisting of the raised chain-stitch border *a* with the 25 transverse filling-threads *b*, as herein shown and described.

In testimony whereof I have hereunto set my hand and seal in the presence of two subscribing witnesses.

SIEGMUND LANDSBERG. [L. S.]
